Primary Examiner — Caron D Veynar*Assistant Examiner* — Katelin G Kloberg(74) Attorney, Agent, or Firm — Banner & Witcoff, Ltd.(57) CLAIM

The ornamental design for a shoe midsole, as shown and described.

DESCRIPTION

FIG. 1 is a front perspective view of a shoe midsole showing my new design;

FIG. 2 is a side view thereof; and,

FIG. 3 is a rear perspective view thereof.

The broken lines immediately adjacent to the shaded area represent unclaimed boundaries of the design. The unshaded polygonal element within the shaded area forms no part of the claimed design. The broken lines showing the remainder of the shoe illustrate portions of the shoe that form no part of the claimed design.
